CIGARETTE HOLDER

Francisco Angel Quiroz, Newark, N. J.

Application October 4, 1949, Serial No. 119,424

4 Claims. (Cl. 131—174)

1

This invention relates to cigarette holders that have means to prevent the falling of the ash or burning tobacco on one's clothes, on the floor or other objects while smoking.

The main object of this invention is to provide a cigarette holder to smoke cigarettes safely, and prevent damage by fire or soiling while smoking.

A further object is to provide a cigarette holder of the character described, that is simple in construction, easy to clean, easy to assemble, safe to hold, nice in appearance and practical to handle.

Another object is to provide a cigarette holder that will cool the smoke, and remove a great part of the tar from the same, in a practical and efficient manner.

Other objects will be obvious in part or pointed out herein.

The invention accordingly consists in the features of construction, combination of elements and arrangement of parts, and the scope of the application which will be indicated in the following claims.

In the following drawings in which is illustrated one of various possible embodiments of the features of my invention:

Fig. 1 is a vertical cross sectional view along the line A—A in Fig. 2, showing in dotted line the relative position of the cigarette.

Fig. 2 is a plan view of the holder in an upright position.

Fig. 3 is a side view in elevation, showing part of the cigarette in position.

Similar reference characters refer to similar parts throughout the drawings.

Referring now to the drawings and more particularly to Fig. 1, the holder comprises a cup 1, which can be made of any suitable material that is a poor conductor of heat, like wood or plastic material. A conical guard sleeve 2 is preferably made of a good conductor of heat and fire proof material like aluminum. A tube 3 is also preferably made of aluminum and a mouth piece 4 is preferably made of a suitable plastic material.

The cup 1 is preferably made slightly conical, to provide a tapered inside seat 5, adapted to match the tapered section below the air supply holes 6 of the guard sleeve 2, to hold said sleeve firmly in position. The bottom part or wall 7 of the cup 1 is made with a certain degree of inclination, preferably adapted to form an inclined seat 8 at an angle to conform with the dotted line 9 that touches the tip of the mouth piece 4. The object of the inclined inner surface of the bottom wall 7 is to prevent the cigarette from rest-

2

ing perpendicularly on a flat surface, and thereby prevent choking of the cigarette or interference with the flow of smoke from the cigarette to the mouth piece. The object of the outside inclined bottom seat 8 is to provide a seat that will rest flat on a table or a similar object, when the tip of the mouth piece touches the same surface. In this manner the holder can be placed and rested on any flat surface while it is being used, and the hot guard sleeve will not touch and damage the surface.

The cup 1 is provided with an outlet tapered hole 11 near the top of the cup, preferably at a right angle from the vertical position of the cup, and adapted to fit tightly on a tapered end of the tube 3. The other end of the tube 3 is also tapered to fit tightly in the tapered hole 12 of the mouth piece 4. The mouth piece 4 may have the form of any conventional mouth piece of a cigarette holder or pipe.

The guard sleeve 2 is preferably made of sheet aluminum in the form of a tapered tube, having the wider end at the top open, and the extreme border bent towards the inside of the tube to form a flange 16 and reinforce it and prevent damage and also to prevent the ashes from falling out of the sleeve when it is in a horizontal position. Towards the bottom end, the guard sleeve is provided with a section 13 having a greater degree of taper, to prevent it from touching the inside wall of the cup, and allow space for the smoke to flow towards the outlet hole 11. The bottom end of the guard sleeve is provided with a short cylindrical section 14 having the proper inside diameter, and adapted to receive and hold the cigarette in position. The guard sleeve is also provided with a number of air holes 6 located just outside of the top of the cup 1, to allow a certain amount of air to enter the guard sleeve to sustain combustion.

The use of the holder is as follows: A cigarette is inserted into the narrow cylindrical section 14 of the guard sleeve 2, as shown by the dotted line 15 in Fig. 1. The cigarette should be placed allowing about $\frac{1}{8}$ of an inch to protrude out at the bottom in order to remove the cigarette butt that is left unburnt in the cylindrical section 14. The cigarette is lighted at the top, and the holder is handled and smoked in the same manner as a pipe. The cigarette will burn until the fire reaches the narrow cylindrical section 14 of the guard sleeve 2. When the fire comes in contact with the metal of the guard sleeve that conveys the heat fast, it will go out and leave a short butt. All the ash of the cigarette will remain

inside of the guard sleeve 2 and can be removed by shaking the holder upside-down over an ash tray or other convenient place. To smoke another cigarette, the guard sleeve 2 is easily removed from the cup 1 by pulling it up, and the cigarette butt is removed by pulling it down. Another cigarette can be inserted in the guard sleeve which is set again in place in the cup 1, and the holder is ready for another smoke.

As all the parts of the holder are put together by means of tapered joints, they can be easily pulled apart and conveniently cleaned with soap and water and a brush, when they become too soiled with tar.

As the holder may take different forms without departing from the scope of the invention, it is to be understood that all matter herein set forth, or shown in the accompanying drawings, is to be interpreted as illustrative and not in a limiting sense.

What I claim is:

1. A cigarette holder of the character described, comprising in combination, a tapered cup having the upper part wider and open and the lower part being closed and including an inclined wall, said cup being provided with an outlet hole located near the top substantially at right angles to the axis of said cup and above the upper point of the inclined wall, a tube engaging the outlet hole at one end by a taper fit and supporting a mouth piece at the other end, a tapered sleeve having the same degree of taper on the outside as the cup has in the inside, with the exception of the lower end of said sleeve which has a greater degree of taper and an end having a small cylindrical section which is the part which holds the cigarette in position, said sleeve having an outside diameter about the middle section equal to the inside diameter of the rim of the cup, so that it can be taper fitted and firmly secured coaxially with the cup, in such a position that the bottom of the sleeve

will be a short distance above the inclined bottom wall of the cup in order to leave enough room for a portion of the cigarette to extend out of the sleeve and provide the means by which the cigarette butts can be removed, said sleeve being provided with a plurality of small holes around the circumference just outside of the cup, said holes being large enough to supply enough air to maintain combustion while the holder is not in use by the smoker.

10 2. A cigarette holder as claimed in claim 1, in which the upper tapered section of the sleeve which fits the taper of the cup does not extend below the lower portion of the outlet hole to provide a smoke passage from the sleeve to the tube.

15 3. A cigarette holder as claimed in claim 1, in which the upper rim of the sleeve is bent inwards to form a flange to prevent ashes from falling when said sleeve is in a horizontal position.

20 4. A cigarette holder as claimed in claim 1, in which the exterior surface of said inclined wall lies in a plane which will intersect the end of the mouth piece to provide means for supporting the holder at rest, and the interior surface of said inclined wall being in an oblique position to the vertical axes of the sleeve and the cigarette, to prevent choking of the cigarette, which might occur if the cigarette were to be positioned perpendicular to the interior surface of the lower wall.

FRANCISCO ANGEL QUIROZ.
